CLAIM

The ornamental design for perforated margin remover for computer paper or the like, as shown and described.

DESCRIPTION

FIG. 1 is a perspective view of the perforated margin remover for computer paper or the like showing my new design with the jaws in the open position;

FIG. 2 is a front elevational view thereof with the jaws shown in the closed position;

FIG. 3 is an end elevational view thereof, the opposite end being a mirror image;

FIG. 4 is an end elevational view thereof with the jaws shown in the closed position;

FIG. 5 is a top plan view thereof;

FIG. 6 is a rear elevational view thereof;

FIG. 7 is a bottom plan view thereof.
